UNITED STATES PATENT OFFICE

2,516,653

HIGH-SPEED COVER TRANSFER MEANS

Justin Simpson and Ralph M. Mero, Chicago, Ill.,
assignors to Continental Can Company, Inc.,
New York, N. Y., a corporation of New York

Application September 28, 1948, Serial No. 51,626

10 Claims. (Cl. 113—114)

1
The invention relates generally to the art of making cans and primarily seeks to provide a novel means for rapidly and accurately transferring covers from the position at which they are deposited one by one from a cover feed means to the position at which they are assembled on the cans to be closed thereby.

It has been the practice heretofore, in the feeding of covers and the assembling thereof on cans to be closed thereby, to drop the covers one by one onto suitable supporting means in the path of a travelling turret lug effective to engage behind the covers and convey them into position for being received on the complementary cans. This practice has been satisfactory when the feeding of the cans and covers was effected at relatively slow rates, but difficulties have been experienced when attempts were made to speed up the feeding of the cans and covers so as to keep pace with the higher speeds at which can lines and closing machines are being operated in some plants at the present time. Some can lines now function at speeds up to four hundred and fifty cans per minute, and closing machines have been designed to keep pace with said lines. It has been found that when covers are dropped in advance of transfer conveyor or turret lugs travelling at such speeds there is a tendency for the covers to bounce away as the fast travelling lugs come against them, with the result that the covers are not always held accurately against said lugs and properly positioned thereby to move into accurate assembly relation to the cans they are intended to cover, and jams occur. It is a purpose of the present invention to provide novel cover feeding or transferring devices in which all possibility of objectionable bouncing and misalignment of covers and cans and jamming thereof is eliminated.

An object of the invention is to provide a cover feeding or transferring means of the character stated in which provision is made for accurately placing each cover between an advance lug and a trailing lug while moving toward the can and cover assembling station, the travelling lugs being driven in time with the travelling cans so as to accurately bring the covers and cans into registering relation at said assembly station.

Another object of the invention is to provide a cover feeding or transferring means of the character stated wherein the covers are supported at their edges only while being moved along between the lugs which also engage them at their edges alone, thereby to assure against drag contact with stationary or relatively moving

2
parts of any portion of a cover having a protective coating ultimately to be presented interiorly of a closed can and which might be crazed or bared by such contact with resulting damage to products contained within such a can.

Another object of the invention is to provide a cover feeding or transferring means of the character stated wherein the lugs of each cover moving and placing set comprise a relatively high trailing lug and a relatively low advance lug, there being included a first encountered high level cover supporting trackway portion along which each cover is pushed solely by a high lug and at a level above that along which the tops of the low lugs travel, a later encountered low level cover supporting trackway portion along which each cover is pushed in position between a high lug and the companion low lug, and an intermediate downwardly inclined cover supporting trackway portion connecting said high level and low level trackway portions and which permits each cover to move downwardly between the lugs of a companion set as the high lug thereof is pushing said cover in edge dragging contact through said inclined trackway portion.

Another object of the invention is to provide in a cover feeding or transferring means of the character stated, novel retarding means tending to retard movement of each cover while passing through the downwardly inclined supporting trackway portion and thereby hold the cover against the high lug as the cover is moving down behind the low lug and bring about an accurate placement of the cover between said lugs without any danger of jamming of a cover on a low lug.

Another object of the invention is to provide a cover feeding or transferring means of the character stated in which the cover retarding means includes a spring pressed retarder shoe which is slotted to permit the cover moving and placing lugs to pass therethrough.

With the above and other objects in view that will hereinafter appear, the nature of the invention will be more clearly understood by reference to the following detailed description, the appended claims, and the several views illustrated in the accompanying drawings.

In the drawings:
Figure 1 is a somewhat diagrammatic plan view showing the improved cover feeding or transferring means and its relation to the cover feeding devices and the closing machine turret.

Figure 2 is a detail plan view illustrating the plate structure which supports and guides the

covers as they are being moved by the transfer turret.

Figure 3 is an inverted plan view illustrating the plate structure shown in Figure 2.

Figure 4 is a fragmentary longitudinal section taken through the cover feedway of the plate structure shown in Figure 2, the section being taken along the center of the cover retarding means.

Figure 5 is a detail vertical cross section taken on the line 5—5 on Figure 4.

Figure 6 is a view similar to Figure 4 illustrating in a somewhat diagrammatic manner the progression of a cover through the high and low level portions of the cover feedway at the positions of the retarding means, a cover being shown on the high level trackway portion in full lines, passing through the downwardly inclined portion of the trackway in dotted lines and on the low level trackway portion in dot and dash lines.

Figure 7 is a fragmentary vertical cross section taken across the high level trackway portion of the plate structure at the position at which covers are deposited thereon by the cover feeding devices.

Figure 8 is a fragmentary vertical cross section taken across the low level feedway portion of the plate structure at the position at which the covers and cans are brought into assembly relation, a can being illustrated as in the progress of being lifted in assembly contact with the complementary cover.

Figure 9 is a diagrammatic plan view illustrating an acceptable means for driving the related parts in properly timed relation.

Figure 10 is a vertical cross section through the drive connections, the section being taken on the line 10—10 on Figure 9.

Figure 11 is a fragmentary perspective view illustrating one turret pocket and the associated set of cover placing and conveying lugs.

Figure 12 is a detail perspective view illustrating the wear plate presenting a downwardly inclined portion disposed to overlie covers as they are moving between the high and low level feedway portions.

In the somewhat diagrammatic illustration in Figure 1, there is shown one practical adaptation of the invention as a means for rapidly feeding or transferring covers from the position in which they are deposited one by one on said means to the position at which they are assembled on the cans to be closed thereby. In this illustration a can feeding means is shown and generally designated A, the cover stack or feed devices are generally designated B, a no-can-no-cover feed control is included and generally designated C, the can and cover transferring means or turret is generally designated D, and the closing and discharging turrets of a six-spindle closing machine are diagrammatically indicated, the closing turret being generally designated E and the closed can discharging turret being generally designated F.

The can and cover conveying turret D includes a rotor body 5 which is peripherally pocketed as at 6 to receive the cans from the usual chain conveyor 7 and timing screw 8 of the can feeding means generally designated A. At the lead or advance side of each turret pocket 6, there is provided a low height placer lug 9 which is removably fixed to the top surface of the turret as at 10 in the manner clearly illustrated in Figures 1 and 11. At the trailing side of each pocket a pusher lug 11 of considerably greater height than

the placer lug 9 is removably fixed as at 12. The pockets 6 of the can and cover transfer turret deliver the cans onto the vertically reciprocable pads 13 of the closing turret E and into the peripheral pockets 14 of said closing turret.

Suitably supported in position for overlying the cover and can transferring turret D is a cover supporting and guiding plate structure generally designated 15. This plate structure is best illustrated in Figures 1 to 7 of the drawings. It will be apparent by reference to Figures 1 and 7 of the drawings that the plate structure includes a well or clearance 16 in which to receive the cover stack or feed means generally designated B, and which includes the cover feeding screws 17 which operate in the recesses 18, and the driver shaft 19 which forms a part of the feed screw driving mechanism. This cover stack or feeding means generally designated B and the no-can-no-cover feed control associated therewith and generally designated C form no part of the present invention and are covered in the copending application for U. S. Letters Patent Serial Number 72,328, filed by Justin Simpson on January 24, 1949. 20 As the covers are fed one by one through the operation of the feed screws 17 they fall or are deposited through the drop opening 20 in the plate structure 15 onto supporting trackways provided on said plate structure. It is to be understood that the plate structure 15 may be formed in one piece, or fabricated from a number of suitably shaped pieces, as desired. The undersurface of the plate structure is milled as at 21 to provide an arcuate can cover guideway which is just wide enough to permit the covers to pass freely therethrough as they are being conveyed by the pusher lugs 11 on the transfer turret rotor 5. The ceiling of the cover feedway is equipped with an arcuate groove 22 to provide clearance for the travelling pusher lugs 11. Intermediately of the ends of the plate there is provided a U-shaped, hardened wear plate 23 which is removably mounted in a recess provided thereon in the ceiling of the plate structure cover guideway in the manner clearly illustrated in Figures 2 through 5 of the drawings. The hardened wear plate 23 is centrally and arcuately grooved as at 24 in register with the groove 22 in the ceiling of the cover feedway to clear the travelling pusher lugs 11 of the transfer turret, 30 and intermediately of its ends said plate is provided with a downwardly inclined portion 25 at opposite sides of the receiving end of a center slot 26 which registers with the slot 27 provided in the ceiling of the plate structure. Through these 35 registering slots a retarder shoe 28 projects downwardly into the path of travel of the covers in the manner clearly illustrated in Figures 4 and 5, and it will be noted that said shoe is centrally slotted as at 29 to clear the pusher lugs 11 of the transfer turret. This slotting of the retarder shoe provides parallel spaced side wings which are shaped in the manner illustrated in Figure 4 to present abruptly downwardly sloping receiving end portions 30, and less abruptly sloping retarding edge 40 portions 31 extending from said portions 30 to the end of said wings. The retarder shoe also is equipped with abutment flanges 32 which are engageable with the top of the plate structure in the manner clearly illustrated in Figures 4 and 5. 45 A housing 33 is secured to the plate structure over the slots 26 and 27, and compression springs 34 interposed between the housing 33 and the top surface of the shoe serve to yieldably depress the same downwardly to the limit permitted by the 50 75 abutment flanges 32.

At the receiving end of the cover feedway, edge rails 35 are secured to the undersurface of the plate structure in the manner clearly illustrated in Figures 2, 3 and 7 so as to overhang the milled guideway 21 as at 36 thereby to provide trackways or supports on which the centrally depressed or countersunk covers will engage at their flanges only in the manner clearly illustrated in Figure 7, the central or depressed portions of said covers extending between the inner edges of said rails 35. It will be apparent by reference to Figures 4, 5 and 7 that the rails 35 provide high level supporting ledges 37 for supporting the covers at their laterally projected flanges during the initial portion of the travel thereof through the supporting and guiding plate structure.

Intermediate overhanging supporting rails 38 also are attached to the undersurface of the plate structure to form continuations of the high level supporting ledges 37 in the manner clearly illustrated in Figures 3 and 4 of the drawings. These intermediate rails have downward inclines 39 which are disposed opposite the advance end portions of the retarder shoe flanges 30, 31. Other overhanging support rails 40 are secured to the undersurface of the plate structure in the manner illustrated in Figures 3 and 4 of the drawings so as to provide low level supporting ledges 41 extending from the delivery ends of the inclined ledge portions 39. The outer support rail 40 may be equipped with an extension 42 projected tangentially with relation to the cover feedway in the manner clearly illustrated in Figures 1, 2 and 3 of the drawings, the same serving to support a hinged top can guide 61 overlying the can intake chain conveyor 7, shown in Figure 1.

Other overhanging support rails 43 extend from the ends of the rails 40 around to and slightly beyond the position at which the assembly of the cans and covers is effected, and it is to be noted by reference to Figures 2, 3 and 8 of the drawings that the rails 43 are narrower than the other rails and are so placed as to more widely space the inner edges 44 thereof than are the inner edges of the other rails. By reason of this manner of shaping and placing the rails 43 suitable clearance is provided for the outwardly projecting top flanges 45 of the cans 46 at the can and cover assembling position in the manner clearly illustrated in Figure 8. Thus as the cans 46 are moved onto the travelling pads 13 of the closing turret E they may be lifted by said pads in the manner clearly illustrated in Figure 8 into assembly relation with the overlying covers. Perfect coaxial relation of the can and cover complements is assured by the engagement of the cans in the turret pocket 6 and the confinement of the covers between the inner and outer surfaces of the plate structure guideway and between the respective placer and pusher lugs 9 and 11. The can and cover complements are thus assembled and lifted through the plate structure clearance 48, and the plate structure also is provided with a clearance or chamfer 48 for clearing the downwardly travelling chuck cover pad 50 which moves into position for engaging each cover in the manner illustrated in Figure 8 incidental to the lifting of each cover and can complement into contact with the chuck 51 opposed by the usual can closing or seaming roll devices generally designated 52. In this manner any misalignment or jamming of cans and covers incidental to the preassembly thereof prior to each double seaming or sealing operation is avoided.

While any suitable means may be provided for

driving the several described parts in suitably timed relation, an acceptable drive arrangement is diagrammatically illustrated in Figures 9 and 10 wherein the main drive gear is indicated at 53. It is to be understood that rotation may be imparted to the shaft on which the gear 53 is affixed in any approved manner (not shown). The driver gear 53 may serve to drive an idler gear 54 which is rotatable with an idler gear 55 disposed to mesh with and impart rotation to a gear 56 which is connected in drive relation with the driver shaft 19 through which rotation is imparted to the cover feed screws 17. The driver gear 53 also imparts rotation to the closing turret and drive gear 57 which is mounted to rotate with the driver gear 58 which meshes with and drives the transfer turret driver gear 59 and also the discharge turret driver gear 60.

In the operation of the apparatus disclosed herein the covers 47 are deposited one by one by the said screws 17 onto the supported rails 35, or rather onto the high level feedway or ledges 37 provided by said rails. See Figure 7. In this manner a cover is deposited in advance of each rapidly travelling pusher lug 11 so as to be conveyed over the feedway supports or rails by said lug. Because of the very rapid rate of travel, the lugs 11 may tend to bounce the stationary cover away from the rapidly moving pusher lugs 11 as the lugs move in contact therewith. The purpose is to place and confine each cover between the leading, low height placer lug 9 and the trailing high level pusher lug 11 of one of the lug sets, but it will be apparent that if no means were provided for bringing and holding the covers against the pusher lugs it would be difficult if not impossible to properly place each cover between the lugs of the respective set in the manner stated, because in bouncing forwardly away from the pushing lug 11 a cover will move into position placing a portion thereof directly over the associated placer lug 9, and jams would occur. In Figure 4 of the drawings a cover is shown in the high level feedway as about to contact the retarder shoe flange portions 30 and as having bounced forwardly out of contact with the rapidly travelling pusher lug 11.

As the covers are pushed by the lugs 11 into contact with the retarder shoe and into the downwardly inclining feedway portion over the downwardly inclined ledges 39, the retarder shoe flange portions 30 and 31 will yieldably engage with the top surfaces of the covers in the manner indicated by dotted lines in Figure 6 to depress the cover in the downwardly inclined trackway portion and cause the trailing edge portion of the cover to be placed and held against the pushing lug 11, and the advance edge portion thereof to move down behind the leading, low height placer lug 9. In this manner each cover passing into the downwardly inclined feedway portion and coming into contact with the spring depressed retarder shoe will be first placed and held against the pushing lug 11 and then be accurately placed between the cooperating lugs 9 and 11 of the particular set.

As each cover is moved through the feedway under the spring depressed retarder shoe it comes to the low level support rails 40, resting only at its lateral flange edge portions on the low level ledges 41 and being supported against tilting by the milled ceiling of the feedway, and being held in accurate confinement between the respective placer and pusher lugs 9 and 11.

It will be apparent that since the covers en-

gage with the supporting rails only at their laterally extended flange edge portions and are engaged only at top portions by the retarder shoe 28 and plate 23, 25, no portion of a cover which is to be presented interiorly of a filled and closed can is engaged in drag contact with any part which might tend to craze or bare protective coatings and thereby present bare metal for contaminating contact with products in the cans.

While one form of the invention has been shown for purposes of illustration, it is to be clearly understood that various changes in the details of construction and arrangement of parts may be made without departing from the spirit and scope of the invention as defined in the appended claims.

We claim:

1. In apparatus for feeding covers for assembly on cans, the combination of a cover supporting feedway over which the covers are conveyed, a conveyor having thereon spaced sets of cover pushing and placing lugs each set comprising a relatively low height placer lug and a relatively high pusher lug spaced to trail behind said placer lug a distance only slightly greater than the diameter of a cover, means for depositing covers on the feedway in position for being engaged by said pusher lugs, said feedway including a high level portion placed at a level higher than that of the tops of the placer lugs but lower than the tops of the pusher lugs, a low level portion wherein covers will travel in confinement between the lugs of the respective sets, and a downwardly inclined portion connecting said high and low level portions and which is effective as covers pass therethrough to cause said covers to move down behind the placer lugs while being pushed by the pusher lugs, and retarding means associated with said inclined portion and effective to engage and tend to retard progress of covers through the inclined portion to momentarily press and hold them against the respective high pusher lug as they are moving down into position behind the respective low placer lug.

2. In apparatus for feeding covers for assembly on cans, the combination of a cover supporting feedway over which the covers are conveyed, a conveyor having thereon spaced sets of cover pushing and placing lugs each set comprising a relatively low height placer lug and a relatively high pusher lug spaced to trail behind said placer lug a distance only slightly greater than the diameter of a cover, means for depositing covers on the feedway in position for being engaged by said pusher lugs, said feedway including a high level portion placed at a level higher than that of the tops of the placer lugs but lower than the tops of the pusher lugs, a low level portion wherein covers will travel in confinement between the lugs of the respective sets, and a downwardly inclined portion connecting said high and low level portions and which is effective as covers pass therethrough to cause said covers to move down behind the placer lugs while being pushed by the pusher lugs, and spring pressed shoe means associated with said inclined portion and disposed to be engaged by covers passing through the inclined portion in a manner tending to retard progress thereof and press and momentarily hold the covers against the trailing high pusher lugs as they are moving down into position behind the low placer lugs.

3. Apparatus as defined in claim 2 and adapted to feed covers having depressed central portions dimensioned to fit within open tops of cans and

flange portions extending outwardly from said central portions and wherein the cover supporting feedway is composed of inwardly directed overhanging rail edges disposed to engage under the flange portions only of said covers with the central portions of the covers extending between them, and the spring pressed shoe means is disposed to engage only top portions of the covers and their flange portions, thereby to avoid the baring of any base metal portion of a cover which is to be subsequently placed in position wherein contamination of can contents by bare base metal contact might result.

4. In apparatus for feeding covers for assembly on cans, the combination of a peripherally pocketed rotary cover and can conveying turret having thereon a set of cover pushing and placing lugs associated with each pocket and comprising a relatively low height placer lug and a relatively high pusher lug spaced apart in a manner for accurately centering a cover over a can in the respective pocket, means for feeding cans to said pockets, an arcuate cover supporting feedway overlying said turret and over which the covers are moved by the pusher lugs, means for depositing a cover in advance of each approaching pusher lug, said feedway including a high level portion placed at a level higher than that of the tops of the placer lugs but lower than the tops of the pusher lugs, a low level portion wherein covers will travel in confinement centered between the placer and pusher lug sets, a downwardly inclined portion connecting said high and low level portions and which is effective as covers pass therethrough to cause said covers to move down behind the placer lugs while being pushed by the pusher lugs, and retarding means associated with said inclined portion and effective to engage and tend to retard progress of covers through the inclined portion to momentarily press and hold them against the respective high pusher lug as they are moving down into position behind the respective low placer lug.

5. In apparatus for feeding covers for assembly on cans, the combination of a peripherally pocketed rotary cover and can conveying turret having thereon a set of cover pushing and placing lugs associated with each pocket and comprising a relatively low height placer lug and a relatively high pusher lug spaced apart in a manner for accurately centering a cover over a can in the respective pocket, means for feeding cans to said pockets, an arcuate cover supporting feedway overlying said turret and over which the covers are moved by the pusher lugs, means for depositing a cover in advance of each approaching pusher lug, said feedway including a high level portion placed at a level higher than that of the tops of the placer lugs but lower than the tops of the pusher lugs, a low level portion wherein covers will travel in confinement centered between the placer and pusher lug sets, a downwardly inclined portion connecting said high and low level portions and which is effective as covers pass therethrough to cause said covers to move down behind the placer lugs while being pushed by the pusher lugs, and spring pressed shoe means associated with said inclined portion and disposed to be engaged by covers passing through the inclined portion in a manner tending to retard progress thereof and press and momentarily hold the covers against the trailing high pusher lugs as they are moving down into position behind the low placer lugs.

6. Apparatus as defined in claim 5 and adapted

to feed covers having depressed central portions dimensioned to fit within open tops of cans and flange portions extending outwardly from said central portions and wherein the cover supporting feedway is composed of inwardly directed overhanging rail edges disposed to engage under the flange portions only of said covers with the central portions of the covers extending between them, and the spring pressed shoe means is disposed to engage only top portions of the covers and their flange portions, thereby to avoid the baring of any base metal portion of a cover which is to be subsequently placed in position wherein contamination of can contents by bare base metal contact might result.

7. Apparatus as defined in claim 5 in which the cover supporting feedway has a flat ceiling overlying the same and in part defining and confining the path of travel of the covers, said ceiling including a removable wear plate overlying the inclined feedway portion and which is longitudinally slotted to permit projection downwardly therethrough of the spring pressed retarder shoe.

8. Apparatus as defined in claim 5 and adapted to feed covers having depressed central portions dimensioned to fit within open tops of cans and flange portions extending outwardly from said central portions and wherein the cover supporting feedway is composed of inwardly directed overhanging rail edges disposed to engage under the flange portions only of said covers with the central portions of the covers extending between them, said rail edges including discharge end portions spaced far enough apart to permit passage upwardly therethrough of the open tops of the cans to be assembled with the covers, and there being included means to lift the cans into assembly contact with the covers while they are disposed flatwise on said rail edges and in centered relation between the placer and pusher lugs on the turret.

9. In apparatus for feeding covers for assembly on cans, the combination of a cover supporting feedway over which the covers are conveyed, a conveyor having thereon spaced sets of cover pushing and placing lugs each set comprising a relatively low height placer lug and a relatively high pusher lug spaced to trail behind said placer lug a distance only slightly greater than the diameter of a cover, and means for depositing covers on the feedway in position for being engaged by said pusher lugs, said feedway including a high level cover supporting portion at a level higher than that of the tops of the placer lugs but lower

than the tops of the pusher lugs, a low level cover supporting portion wherein covers will travel in confinement between the lugs of the respective sets, and a downwardly inclined portion between said high and low level portions and disposed to support covers and to at least in part overlie and be contacted by said covers as they pass from said high level portion to said low level portion and which is effective as covers contact said overlying part to retard movement of any cover moving ahead of the respective pushing lug to urge it back against said pushing lug and cause it to move down behind the cooperating placer lug.

10. In apparatus for feeding covers for assembly on cans, the combination of a peripherally pocketed rotary cover and can conveying turret having thereon a set of cover pushing and placing lugs associated with each pocket and comprising a relatively low height placer lug and a relatively high pusher lug spaced apart in a manner for accurately centering a cover over a can in the respective pocket, means for feeding cans to said pockets, an arcuate cover supporting feedway overlying said turret and over which the covers are moved by the pusher lugs, means for depositing a cover in advance of each approaching pusher lug, said feedway including a high level cover supporting portion placed at a level higher than that of the tops of the placer lugs but lower than the tops of the pusher lugs, a low level cover supporting portion wherein covers will travel in confinement centered between the placer and pusher lug sets, and a downwardly inclined portion between said high and low level portions and disposed to support covers and to at least in part overlie and be contacted by covers as they pass from said high level portion to said low level portion and which is effective as covers contact said overlying part to retard movement of any cover moving ahead of the respective pushing lug to urge it back against said pushing lug and cause it to move down behind the cooperating place lug.

JUSTIN SIMPSON.
